BATTERY OVERLOAD EDUCATIONAL BOARD

Jack N. Holcomb, Fort Lauderdale, Fla., assignor to
National Intelligence Academy

Filed Oct. 15, 1974, Ser. No. 514,901

Term of patent 14 years

Int. Cl. D19—07

U.S. Cl. D19—64

FIG. 1 is a left front perspective view of a battery overload educational board showing my new design;

FIG. 2 is a right front perspective view thereof; and

FIG. 3 is a rear perspective view thereof shown on a slightly reduced scale.

I claim:

The ornamental design for a battery overload educational board, as shown and described.
